Oliver L. Pinney.

United States Patent Office.

OLIVER L. PINNEY, OF BRUNSWICK, OHIO.

Letters Patent No. 70,115, dated October 22, 1867.

IMPROVEMENT IN LIFTING-JACK.

The Schedule referred to in these Letters Patent and making part of the same.

Be it known that I, OLIVER L. PINNEY, of Brunswick, in the county of Medina, and State of Ohio, have invented a new and useful Improvement in Lifting-Jacks; and I do hereby declare that the following is a full, clear, and exact description of the construction and operation of the same, reference being had to the annexed drawings, making a part of this specification, in which—

Figure 1 is an elevation of one side, and

Figure 2 is an elevation of the opposite side.

Into the bed-piece A is firmly framed the wedge-shaped piece B. On the edge of this are fastened two strips of iron, or other metal, C C. A lever, D, turns the segment of a toothed wheel, E. To the movable piece F are attached four metallic pieces G G G G, having grooves on their inner sides to receive the edges of the iron strips C C. To the same piece is firmly fastened the strip H, toothed on one side to fit into the teeth of the segmental wheel E.

By bearing down the lever D the wheel E is turned, and the movable piece F is raised. When thus raised it is held in its place by the link I, fastened to the piece F, as represented, and having a slot in its lower end, in which works a pin, K. When the piece F is raised to the proper height the points M, K, and L form a triangle, with its apex towards the long end of the lever D, and consequently any downward pressure on the piece F will tend to keep down the long end of the lever D.

What I claim as my invention, and desire to secure by Letters Patent, is—

The lever D, wheel E, and toothed piece H, in combination with the link I, substantially as set forth.
